LIGHTING UNIT

Jacob H. Blitzer, New York, N. Y., assignor to
 Lightolier Company, New York, N. Y., a corpora-
 tion of New York

Application November 10, 1934, Serial No. 752,422

9 Claims. (Cl. 240—78)

My present invention relates to lighting units, primarily to fixtures suspended from the ceiling, although in its broader aspect the invention is also applicable to various types of lamps.

5 It is among the objects of the invention to provide a lighting unit by which scientifically correct and uniform distribution of light may be economically effected, by use of a fixture which is simple and decorative in appearance.

10 Another object is to provide a lighting unit of the above type, affording a correct combination of indirect and diffusion illumination, by which regions of shadow at any part of the room are substantially precluded and the fixture in use 15 may be directly viewed without glare.

Another object is to provide a fixture of the above type made up of few simple structural parts, readily assembled, and when installed gives the appearance of an entity of metal and glass 20 without revealing the shadow of any struts, hangers, screws, or other connectors by which such parts are held together.

Another object is to provide a fixture of the above type, the translucent or glass elements of 25 which may be conveniently cleaned inside and outside without the need for disassembling the unit.

A feature of the invention is the use of a composite shade bowl made up of a plurality of zone 30 segments, some of which are opaque, preferably of metal, and others translucent, preferably of glass or other vitreous material, the rim of each zone segment contacting the contiguous rim of the neighboring one. The shade is preferably 35 supported from one of the zone segments, the remaining segments resting by gravity thereon.

It is another feature of the invention to provide baffle shield means within the translucent segment or segments to intercept the direct rays 40 of the lamp, each shield preferably integral with a contiguous metal zone segment.

In a preferred application to a suspended lighting fixture, the polar cap segment of the shade bowl is suspended by hangers from near its periphery and sustains at its peripheral ledge the inner rim of a vitreous zone segment, which in the preferred embodiment, in turn supports a metal rim zone piece provided with an integral baffle shield surrounded by the translucent seg- 45 ment.

50 Preferably the hangers are so constructed that upon removal of the bowl unit from its support appropriate enlargements on said hangers serve to sustain the smaller zone segments in spaced relation by gravity from the rim piece and thus

afford ready access to the interior of all parts for convenience in cleaning.

In the accompanying drawing, in which is shown one of various possible embodiments of the several features of the invention:

Fig. 1 is a view in longitudinal cross-section of a preferred embodiment of the fixture.

Fig. 2 is a view similar to Fig. 1 showing the relation of the bowl elements when disconnected for convenience of cleaning.

Fig. 3 is an enlarged detail view partly in section showing the connection of the hanger to the polar cap.

Fig. 4 is an enlarged detail view taken on line 4—4 of Fig. 2.

Referring now to the drawing, there is illustratively shown a lamp socket 10 supported by a fitting 10' from tube 11. Socket 10 has a shield tube 12 thereover from beyond the rim of which the lamp bulb 13 protrudes. The lamp socket 10, according to familiar practice is preferably adjustable in height, so as to permit proper coordination of the lamp bulb, depending on its length, with respect to the shade bowl, now to be described.

The shade bowl, which is of composite construction, is preferably suspended from the socket shield 12 usually, by three hangers s, to be more fully described below. The composite shade bowl is preferably supported from the polar cap segment thereof, shown as a shallow bowl 17 of sheet metal, preferably aluminum. Said polar cap segment is provided with a peripheral support ledge 18, for sustaining the inner rim of the translucent or glass zone segment 19. The hangers extend through corresponding apertures 20 through embossments 22, closely contiguous to the support ledge 18 of the polar cap, the polar cap resting upon buttons 21 threaded upon the lower ends of the hangers, and which extend into said embossments 22. Preferably the metal of the buttons 21 is extended outward at flange 23 to line the perforations 20 about hanger s, so as to assure a light-tight joint.

45 In the particular embodiment shown, the rim zone segment 25 also preferably of aluminum, rests at its inner peripheral shoulder 26 upon the outer rim of the translucent zone segment 19. In a preferred embodiment, element 25 has an integral extension preferably in the form of a frusto-conical skirt 27 extending inward along the width of the translucent segment 19 and serving as a baffle to prevent brilliant illumination 50 of said segment, the light penetrating under the

rim 28 of said baffle adjacent the bulb for illumination of the translucent piece by diffusion.

The hangers 8 preferably include hanger wires s^2 provided with eyes 33 at the upper ends thereof, said eyes being hung on the hooked ends 32 of hanger rods s' secured to the shield tube 12. While the hanger rods may be soldered or welded to the shield tube, I have shown said rods introduced through a corresponding aperture 31 in the shield tube and provided with an enlarged head as at 30 at the upper ends thereof, serving as a support, said hanger rods by said arrangement being supported to extend obliquely outward, as shown. The reflector is, of course, provided with 15 corresponding small apertures 34 to accommodate the hanger wires s^2 . The wires s^2 are inserted downward through said apertures, and after application of the polar cap 17, the buttons 21 are threaded upon the lower ends of said 20 hanger wires and upset at 23 as above described.

Though the operation will be manifest from the above description, it will be briefly summarized. The entire area of the rim segment 25 with its baffle 27 being of dull aluminum, serves 25 not only as a reflector for indirect illumination, but by reason of the unpolished surface of the metal, serves to diffuse the light without substantial shade demarcation. Such light as passes from the lamp under the inner rim 28 of the 30 baffle 27 causes a soft glow of the translucent segment 19, which not only adds beauty to the fixture but diffuses illumination downward to prevent any possible shadow due to the polar cap segment 17 which extends immediately under the lamp bulb 35 13. With the use of this fixture substantially uniform shadowless illumination is afforded throughout the room.

When it is desired to clean the bowl it is merely necessary to unhook the hanger wires s^2 at their 40 eyes 33 from the hooks 32, thereby disconnecting the bowl. The bowl does not, however, thereby become disassembled, for the polar cap 17, and the translucent segment 19 are sustained by the hanger eyes 33, as best shown in Fig. 2, resting 45 on the reflector skirt 27 of the rim piece 25, when the bowl is grasped by said rim piece. Thus the translucent segment 19 drops away from the reflector through a distance limited by the length 50 of the hanger wires s^2 , whereby the individual shade parts may be readily cleaned inside and outside without disassembly, and after cleaning may be reapplied by merely hooking the three hanger wires to the respective hooks 32 of the hanger rods.

It will be understood that while the composite shade bowl is shown as having only three zone segments, one of which is translucent, the principle of the invention could be applied to shade bowls of any number of zone segments 55 greater or less than three.

It is also apparent that the various zone segments are not necessarily segments of a sphere or of a modified ellipsoid as shown, but may present any of a wide variety of contours, and that 60 the rims of the respective segments are not necessarily strictly plane as shown but may be scalloped or given any of a wide variety of configurations for ornamental effects readily produced by any capable designer.

It will also be understood that the elements of 70 the composite bowl may be held together by the use of any appropriate rigid extension from the rim segment to the neighborhood of the polar cap segment and that a baffle plate need not necessarily be employed for that purpose.

While the invention has its preferred application to pendant ceiling fixtures, it is clear that it is applicable to floor lamps, table lamps, wall lamps and in numerous relations, and the term "bowl" as used in the broader claims embraces 5 within its scope an inverted bowl such as is used for upright lamps.

It will thus be seen that there is herein described apparatus in which the several features of this invention are embodied, and which apparatus in its action attains the various objects of the invention and is well suited to meet the requirements of practical use.

As many changes could be made in the above construction, without departing from the scope 15 of the claims, it is intended that all matter contained in the above description or shown in the accompanying drawing shall be interpreted as 20 illustrative and not in a limiting sense.

Having thus described my invention, what I 25 claim as new and desire to secure by Letters Patent is:

1. A lighting fixture including a pendant lamp bulb having a socket, a shield about said socket, a plurality of hangers supported by said shield, a composite shade element including a metal polar cap segment directly sustained near its periphery by said hangers, a translucent zone segment resting at its inner periphery on the rim of said polar cap and wholly supported thereby and a metal rim zone piece having a shoulder at its inner periphery resting on the outer periphery of said translucent segment and wholly supported thereby, said rim zone piece having integral therewith a baffle skirt intervening between the main area of said translucent segment and said lamp bulb.

2. The combination set forth in claim 1 in which the baffle skirt is frusto-conical in shape with its inner rim contiguous to the lamp bulb 40 and in which the hangers extend through corresponding apertures in said baffle piece.

3. A composite shade bowl unit for a lighting fixture including a polar cap segment and a plurality of zone segments, some of metal and the rest of translucent material, the polar cap piece having a rim ledge for sustaining the inner periphery of the contiguous zone segment, the outer rim zone of said shade being of metal and including an inner shoulder resting on the rim of the contiguous segment and means for sustaining said composite shade and comprising hangers extending through corresponding apertures in the polar cap segment, closely contiguous to the supporting ledge thereof and carrying enlargements 55 at the lower ends thereof serving to close said apertures, said polar cap segment wholly supporting the remaining segments of said shade bowl unit.

4. A lighting fixture comprising a pendant lamp bulb having a socket, hangers fixed in one end with respect to said socket and extending obliquely to clear said lamp bulb, a shade bowl comprising a metal polar cap segment having a peripheral support ledge and sustained near its periphery by said hangers, a translucent shade zone segment resting at its inner periphery on said ledge, a metal rim zone segment having a shoulder at its inner periphery resting on the outer rim of said translucent segment, and a frusto-conical baffle piece integral with said rim piece encircled by said translucent segment and having perforations for said hangers.

5. A lighting fixture comprising a pendant lamp bulb having a socket, a shield for said socket,

hanger rods attached at their upper ends in corresponding apertures of said shield and extending obliquely to clear said bulb, a composite shade including a metal polar cap segment having a peripheral support ledge, said rods having hanger wires detachably connected thereto and extending through corresponding perforations adjacent said support ledge and having enlargements thereon, sealing said perforations and serving as rests for said polar cap, a translucent glass zone segment resting at its inner periphery on said rim ledge, a metal rim zone segment having a shoulder resting on the outer periphery of said translucent segment and a frustro-conical skirt integral with said rim segment with its inner periphery in the neighborhood of the lamp bulb.

6. A lighting unit including a composite bowl having an opaque polar cap, an opaque rim having extension means integral therewith projecting within the bowl to beyond the periphery of the polar cap, hangers directly supporting said polar cap, said hangers having enlargements above the extension means, said enlargements by co-action with said extension means affording clearance but locking the complete separation of the segments of said bowl when the hangers are disconnected from their respective supports.

7. A lighting unit including a composite bowl having an opaque polar cap, an opaque rim segment and an intervening translucent segment, said rim segment having a unitary reflector skirt encircled by said translucent segment and extending to within the rim of the polar cap, a plurality of hangers, each including two elements, an

upper fixed element and a lower disconnectable elements attached at its lower end to the polar cap and extending through the reflector skirt, the upper ends of said lower hanger elements having enlargements for connection to the corresponding fixed hanger elements, whereby upon disconnecting the lower hanger elements from their respective supports the said enlargements will serve to limit the separation of the lower bowl segments with respect to the rim segment.

8. The combination set forth in claim 7 in which the upper ends of the lower hanger elements have eyes to be hooked with respect to the lower ends of the fixed hanger elements, the planes of said eyes being substantially at right angles to elongated slots therefor in the reflector skirt.

9. A lighting unit comprising a lamp socket having an enclosing shield tube, hanger elements affixed at their upper ends to said shield tube and extending obliquely outward therefrom and having hooks at the lower ends thereof, a composite shade bowl including a metal polar cap having hanger wires affixed at the lower ends thereof near the rim of said polar cap and having eyed upper ends coacting with the lower ends of the fixed hanger elements, a translucent shade segment resting on the rim of said polar cap, an opaque rim segment resting on the upper rim of said translucent segment and having an integral reflector skirt, said hanger wires extending through corresponding apertures in said skirt.
